UNITED STATES PATENT OFFICE.

CHINGALPAT NÂGARATHNAM ACHÂRI AND CORNELIUS EDWARD CARDEW,
OF INSEIN, LOWER BURMA, INDIA, AND ILLIUS AUGUSTUS TIMMIS, OF
LONDON, ENGLAND.

BRAKE-RIGGING FOR RAILWAY-VEHICLES.

No. 796,621.

Specification of Letters Patent.

Patented Aug. 8, 1905.

Application filed September 16, 1904. Serial No. 224,767.

To all whom it may concern:

Be it known that we, CHINGALPAT NÂGARATHNAM ACHÂRI and CORNELIUS EDWARD CARDEW, of the town of Insein, Hanthawâdi district, Lower Burma, India, and ILLIUS AUGUSTUS TIMMIS, of London, in the county of Middlesex, England, subjects of the King of Great Britain, have invented new and useful Improvements in Brake-Rigging for Railway-Vehicles, of which the following is a specification.

The objects of our invention are to make brake-gearing for railway-vehicles so that it shall automatically increase or decrease the thrust of the brake-blocks in proportion as the load in or on a vehicle is increased or lessened.

It is well known that railway and other brakes when operated exercise a force which is practically constant, being dependent on the manual or air or other force employed and not on the varying load carried by the vehicle.

With these facts and with these objects in view we construct the brake-gearing so that as the load carried by a vehicle increases the leverage from the pull (or push) rod, which actuates the brakes, also increases, and vice versa, so that the braking or stopping power exercised on the different vehicles of a train will vary in proportion to the load carried.

In the accompanying drawings, illustrating our invention, Figure 1 is a vertical longitudinal sectional view of the mechanism embodying our invention applied to a railway-carriage. Fig. 2 is a plan view. Fig. 3 is a vertical transverse section on the line B B of Fig. 1. Fig. 4 is a vertical transverse section on the line C C of Fig. 1. Fig. 5 is a vertical transverse view in section on the line A A of Fig. 1. Fig. 6 is a side elevation of a modified brake-rigging structure. Fig. 7 is a horizontal section of the structure shown in Fig. 6.

The brake-beams K' and K², as shown in Figs. 1 and 2, are suspended by the hangers l', l², l³, and l⁴, from the brackets b', b², b³, and b⁴, projecting from the bolster A of the truck or bogie supported by said brackets, and are pivoted on pins X', X², X³, and X⁴. A graduating lever g is pivoted by pin X⁵ on bracket C, fixed on bolster A, and also pivoted by pin X⁶ through a slotted hole a to the levers H'

and H², which are located adjacent to one pair of the bogie-wheels. Corresponding levers H³ and H⁴ adjacent to the other wheels are pivoted by pin X⁷ to the bolster-bracket C². The spring T couples and operates to release the brake-blocks. The rod N by means of pins X¹⁰ and X¹¹ connects with the levers H', H², H³, and H⁴.

Automatic adjusting arms q' and q² are pivoted by pin X¹² onto bracket C², fixed to the truck-bogie. The body of the vehicle presses downward on arms q' and q² at, say, their centers and at one end by means of pin X¹³. Said arms are pivoted to the upper end of a link p. At the lower end of link p is a slotted hole p², and by means of pin X¹⁴ said link is coupled to arms f' and f². The arms f' and f² extend horizontally both ways from said pin X¹⁴, and at one end they are coupled by means of pin X¹⁵ through slots h³ to the hanging brackets a' and a², attached to the body of the vehicle, while at their other ends they are connected by pin X¹⁶. These arms f' and f² operate pin X¹⁶ up and down against the edge of the lever g, which is pivoted on X⁵. They press automatically against lever g by means of the balance-weights d' and d², attached to their extensions d⁴ d⁵. Therefore as a downward thrust (through an increasing load) is applied on arms q' and q², which are pivoted on the fixed pin X¹² at one of their ends, the pins X¹³ and X¹⁴ and link p are forced downward and the arms f' and f², pivoted at X¹⁵ in slotted holes on brackets a' and a², are forced downward at X¹⁴, and consequently pin X¹⁶ is forced downward on the face of lever g. It is thus evident that when the brake-gearing is operated by a pull on the rod e in the direction of the arrow the arms f' and f² are pulled and pin X¹⁶ is also pulled against and operates lever g—say on the lower dotted line marked "loaded;" but as lever g is connected to levers H' and H² by pivotal pin X⁶ the leverage on H' and H², which operate the brake-beams, is greater than it would be if arms f' and f² were at any point above the dotted line marked "loaded."

In the modification shown in Figs. 6 and 7 the pull-rod E is attached by the long pin P' to the levers H H, which are pivoted at their upper ends to the fixed bracket B³ on the truck-bogie by two pins P² P². Passing

through levers H H near their centers is a pin X²⁰, which is supported by levers H H in horizontal slots V, and between levers H H are two long arms f' and f², the rear ends of which are joined by the pin X²¹, and this pin is in contact with the rear faces of the center parts of levers H H. The forward ends of the levers f' and f² are joined by the pin X²², which is in contact with the front faces of quadrants q q. Pin X²⁰, supported by levers H H, itself supports arms f' and f², which are also provided with horizontal slots V. On the pin X²⁰ are pivoted two floating levers R' R', the upper ends of which are joined by pin X²⁶ to the forward end of the brake-arm G'. The lower ends of levers R' R' are joined to the rear end of the long push-rod L by the pin X²⁵. The front end of rod L, which is slotted, as shown at l, is supported at the bottom of the bracket B³ by the pin X²⁷. On bracket B³ are also supported near their centers, by pin X³⁰, the levers R² R². The lower ends of R² R² are joined by pin X²⁸ to lever L in a slot. The upper ends of levers R² R² are joined by pin X²⁹ to the brake-arm G². The quadrants q q have a pin X³³ through them, and on it and between quadrants q q there is a link K, the other end of which is on pin X²⁰, already referred to, and said link is between the levers R' R'. The upper ends of quadrants q q have a pin X³² through them, which is supported by the upper ends of brackets R³ R³. These brackets R³ R³ are connected at their lower ends by pins X³³ and X³⁴, which are supported in the slots l' in the long rod L. In the arms f' and f² there is a pin X³¹, and on the same pin and outside arms f' and f² are fixed the rear ends of two levers f³ and f⁴. In the forward ends of levers f³ and f⁴ is a pin X²⁴, which is supported in a slot l' on bracket B³. About a third of the distance from the rear ends of levers f³ and f⁴ they have two pins X²³ X²³ through them, and these pins pass through brackets B B and support them on it. Brackets B B are attached to the bogie-bolster. The working of this arrangement is as follows: When rod E is pulled, levers H H pull pin X²¹ and arms f' and f², and so pin X²² at the front end of f' and f² presses against and moves quadrants q q. Thus link K is moved lengthwise and this moves pin X²⁰, sliding in arms f' and f², and levers H H, thus moving the floating levers R' R' to the rear and causing brake-arm G' to put on the brakes. At the same time pin X²⁵ at the lower ends of levers R' R' pulls lever L and through pin X²⁸ works levers R² R², which pivot on pin X³⁰, and the brake-arm G² also puts on its brake; but if the brackets B B are forced downward by a greater load in the vehicle then the pins X²³ X²³ force the levers f³ and f⁴ downward, and as the latter pivot on pin X²⁴ in fixed bracket B³ their rear ends

on pin X³¹ force arms f' and f² a still greater distance than the downward travel of brackets B B, and as arms f' and f² are confined in their vertical movement by pin X²⁰ the forward ends of f' and f² and the pin X²² through them is forced down on the face of the quadrants q q. For instance, if bracket B forces pins X²³ down one-fourth inch then X³¹ is forced down one-half inch and f' and f² are forced down, causing pin X²² to descend one and five-sixteenths inches, so that the leverage on quadrants q q has been increased from one and one-eighth inches from their fulcrum X²² to two and three-eighths inches. Thus an extra load which causes a deflection in the bearing-springs of one-fourth inch increases the force of the pull of the pull-rod E by over one hundred per cent.

It is clear that the mechanical equivalents to increase the length of travel of the self-graduating arm and to increase (or diminish) the leverage of the pull by rod e or its equivalent and the consequent force on the brake-blocks can be varied almost indefinitely; but the principles of our invention are clear and new. They are employing a falling (or rising) arm or arms to conform to the rising or lowering of the body of a vehicle as the load in it is lessened or increased, and to multiply, if necessary, that travel of the body, and an arrangement whereby the leverage—i. e., the pull or push of the rod or its equivalent—which actuates the brake-gearing is increased or diminished as the load increases or diminishes, and by consequence the force on the brake-blocks is increased or lessened in proportion to the load carried.

In Figs. 1 and 2 the levers l' l² and l' l⁴ have each pair a positive motion given to them and to their respective beams K' and K², whereas in Figs. 6 and 7, with the floating-levers R' R' in conjunction with link K and the brackets R³ R³, another mechanical combination is effected. Other combinations can be arranged; but

What we claim to have invented and what we claim is—

1. In brake-rigging for railway-vehicles, the combination with the suspended brake-beams, and the live levers through which the brake-beams are operated, of a graduating lever, attached to the live levers, depressible levers connected to the pull-rod of the brake, and provided with pins which bear on the face of said graduating lever, and means whereby said depressible levers are depressed in proportion to the weight of the load upon the vehicle, and the leverage on the graduating lever correspondingly increased.

2. In brake-rigging for railway-vehicles, the combination with the pull-rod, through which power is applied to the brake-beams, of a graduating lever, connections with the pull-rod which bear on the face of said lever, and

means connected with said lever for communicating power to operate the brake-beams, and for changing the leverage of the pull-rod connections, according to the weight of the load carried by the vehicle.

3. In brake-rigging for railway-vehicles, the combination with the brake-beams and pull-rod, of means for lessening or increasing the force operating the brakes according to the weight of the load and a counterpoise weight or weights connected with and operating in conjunction with said means to automatically maintain the leverage - varying parts in proper relation.

In testimony whereof we have hereunto

signed our names in the presence of subscribing witnesses.
